UNITED STATES PATENT OFFICE.

JOSEPH S. LACH, OF BRIDGEPORT, CONNECTICUT, ASSIGNOR TO THE YALE & TOWNE MANUFACTURING COMPANY, OF STAMFORD, CONNECTICUT.

AUTOMOBILE LOCK MEANS.

Application filed August 4, 1926. Serial No. 127,083.

This invention relates to improvements in automobile locks, one object of the invention being to provide simple and efficient means which shall be operable simultaneously to lock the electric ignition circuit open and to lock the control means for the clutch.

With this and other objects in view, the invention consists in certain novel features of construction and combinations of parts as hereinafter set forth and pointed out in the claims.

In the accompanying drawings;

Figure 1 is a side view showing an embodiment of my invention;

Figure 2 is a front view;

Figure 2^a is a view of the operating shaft lever or handle 8;

Figure 3 is a back view;

Figure 4 is a plan view;

Figure 5 is a face view showing the dial and associated parts;

Figures 6 and 7 are detail views showing the circuit breaker and operating parts;

Figures 8, 9 and 10 are views illustrating locking means for the dial lever shaft,

Figure 11 is a view partly in elevation and partly in section showing the dial lever shaft and locking means therefor, and

Figure 12 is a detail view showing the coupling structure 49.

My improved locking mechanism comprises a suitable frame or casing 1 to be secured to the instrument board 2 of an automobile, and a dial or front plate 3 is employed and provided with a suitable opening for the accommodation of the plug or rotatable member 4 of a cylinder lock 5, the body portion of the latter being secured within the frame or casing 1. The dial or front plate 3 is also provided with an opening for the accommodation of the projecting end 6 of an operating shaft 7, the latter being suitably mounted in the frame or casing, and the projecting end 6 of said shaft receives a manually operable lever or handle 8.

The frame or casing 1 has secured there-

upon, a cover plate 9 which carries two binding posts 11, 11, to receive terminal wires 12, 12 in the electric ignition circuit. The binding posts 11 are provided at their lower or inner ends with heads which form contacts 13 for cooperation with contacts 14 on a plate or bar 15, whereby the electric ignition circuit may be opened as shown in Figure 6 or closed as shown in Figure 7. The plate or bar 15 of the circuit breaker or switch is carried by a block or head 16 and the latter carries a plunger 17 which normally engages the peripheral portion of a disk 18 keyed to the operating shaft 7, said disk serving to retain the circuit breaker closed under normal conditions, as indicated in Figure 7. The disk 18 is provided with a notch 19 having a beveled wall 20 and a radial wall 21, so that when the shaft 7 is turned in the direction indicated by the arrow on Figure 7, said notch will become disposed under the plunger 17 and permit said plunger to enter the same, causing the circuit breaker to open the electric ignition circuit, as indicated in Figure 6. In order that the head or block 16 and the contact plate or bar 15 of the circuit breaker may be positively moved to the positions shown in Figure 6 to open the electric ignition circuit, springs 22 may be provided, said springs having seats in sockets in the cover plate 9 and the block or head 16 as shown in Figure 1.

The shaft 7 also carries a disk 23 having a notch 24, the ends of which form shoulders 25, 26, and diametrically opposite the notch 24, the disk 23 is provided with a V-shaped notch 27. A vertically movable plunger 28 is suitably mounted in the frame or casing 1 and pressed upwardly by a spring 29 so that its upper end is caused, under certain conditions, to engage in the notch 24 of disk 23 and thus lock the shaft 7 against turning. The plunger 28 is notched as at 29^a to provide a shoulder 30, which is engaged by a roll-back cam 31 carried by the rotatable key-controlled member 4 of the cylinder lock 5. The plunger 28 is also provided,

near its upper end, with a shoulder 32 to be engaged by a spring-pressed plunger 33 for the purpose of holding the locking plunger 28 out of engagement with the disk, temporarily during the operation of the mechanism. The plunger 33 passes through a guide 34 and carries an enlargement 35, between which latter and the guide 34, a spring 36 is located. The disk 18 carries a laterally projecting lug 37 which, during the operation of the shaft 7, will engage the enlargement 35 on the plunger 33 and move the latter away from the shoulder 32 of locking plunger 28.

When the parts are in the positions shown in Figures 6 and 8, the electric ignition circuit will be open and the shaft 7, by which the circuit breaker is controlled, will be locked against turning. Under these conditions, the automobile cannot be started, because the electric ignition circuit is open and locked in such condition. In order, however, that the clutch yoke trunnion of the car shall be, at the same time, locked against operation, the instrumentalities now to be described are employed.

The frame or casing 1 is provided with a diagonally disposed portion 1^a, in which is a diagonal plate 38 on which a slide bracket 39 is movable, a spring-pressed ball or member 40 being employed to maintain said bracket in proper relation to the plate 38. A tube 41 secured to the casing member 1^a serves to protect a rod 42, the latter being connected at its upper end with the slide bracket 39 so as to be moved thereby and the lower end of this rod is connected with a spring-controlled locking bar or member 43 to be moved into locking relation to the trunnion 44 of the clutch yoke, which latter is operable by a pedal lever, as is well understood in the art. The hub 45 of a roll-back 46 is mounted in the plate 39 and said roll-back carries a roll-back pin 47 which enters a cam slot 48 in the slide bracket. A coupling 49 is pivotally connected at one end with one end of the operating or control shaft 7 and at its other end, said coupling is loosely connected with the roll-back hub 45. The coupling 49 comprises a member 49^a to engage the roll-back hub 45 and a member 49^b pivotally connected at one end to the member 49^a by a pivot pin 49^c and at its other end pivoted to the shaft 7 by a pivot pin 49^d, the pivot pins 49^c and 49^d being disposed at right angles to each other. The operating or control shaft 7 is thus connected with the roll-back hub 45 by means of what is, in effect, a universal coupling.

It may be assumed that the circuit breaker has been opened as shown in Figure 6 and locked in such position by cooperation of the plunger 28 with the notched disk 23 as shown in Figure 8, and that the clutch yoke trunnion has been locked by the locking bar

43 as shown in Figure 1. Under such conditions the automobile will be effectually locked against operation. To effect unlocking for placing the car in operable condition, a key 50 will be inserted into the plug 4 of the cylinder lock 5 and turned to draw the plunger 28 out of the notch 24 of disk 23 and as this plunger reaches its lowest position, the plunger 33 will become disposed over the shoulder 32 of plunger 28 and hold the latter in its depressed position (see Figure 9). The key may now be withdrawn. In order to prevent leaving the key in the lock, where it can be stolen or its number noted for the purpose of obtaining a duplicate, the lock is so located with respect to the lever 8 on the operating shaft that the head of the key will be in the path of movement of the lever 8 on the control or operating shaft 7, thus preventing a sufficient movement of the latter to accomplish the complete operation of the devices controlled from said shaft, while the key is in the lock.

When the shaft 7 shall have been unlocked as previously explained and the key removed, the operator will turn said shaft by manipulation of the lever or handle 8, after having depressed the pedal lever which controls the operation of the clutch yoke, to disengage the clutch. As the shaft 7 turns, the lug 37 on the disk 18 will engage the enlargement 35 on the spring-pressed plunger 33 and withdraw the latter to release the plunger 28. The releasing of the plunger 28 will occur after the notch 24 in disk 23 shall have passed the upper end of said plunger, and upward movement of the latter will now be prevented by engagement with the periphery of said disk until the shaft 7 and disk 23 shall have completed their throw or half revolution, at which time, the upper end of the plunger 28 will enter the V-shaped notch 27 in the disk 23 and the shaft thus be held against accidental movement. During the turning of the shaft 7, the disk 18 which is keyed thereto will turn and the beveled wall 20 of the notch 19, will force the circuit breaker to its closed position as shown in Figure 7, thus closing the electric ignition circuit, the circuit breaker being maintained closed by engagement of the plunger 17 with the periphery of the disk 18.

During the said turning movement of the shaft 7, motion will be imparted, through the universal coupling 49 to the roll-back cam 46 and cooperation of the roll-back pin 47 with the cam slot 48 in the slide 39, will cause vertical movement of the latter until the pin becomes disposed on a dead center over the axis of the roll-back hub. During such vertical movement of the slide, the locking bar 43 will (through the medium of the rod 42) be raised from interlocking relation with the clutch yoke and the pedal

may now be operated in the usual manner to control the clutch.

To move the parts from normal operative position, for rendering the electric ignition circuit and clutch yoke and pedal lever inoperative (as indicated in the drawings), the use of the key is not necessary, it being sufficient only to turn the lever or handle 8 counter-clockwise to effect a half turn of the 10 shaft 7 and the parts carried thereby and connected therewith.

Having fully described my invention what I claim as new and desire to secure by Letters Patent, is:—

15 1. In automobile lock means for the electric ignition circuit and the clutch control means, the combination with a circuit breaker for the electric ignition circuit and a locking member for the clutch control means, of a manually operable shaft, a notched disk carried by said shaft and co-operable with the circuit breaker, a slide bracket, connecting means between said slide bracket and the clutch locking member, connections between said slide bracket and said shaft, and means for locking said shaft.

20 2. In automobile lock means, the combination with a circuit breaker for the electric ignition circuit and a locking member for the clutch control means of the automobile, of a manually operable shaft, an operating lever on said shaft, operating connections between said shaft and the circuit breaker, operating connections between said shaft and said clutch locking member, a key lock, and means operable by said lock for locking said shaft, said lock being so located relatively to the lever on said shaft, that the latter will be prevented from complete operation when the key is in the lock.

25 3. In automobile lock means, the combination with a circuit breaker for the electric ignition circuit, of a manually operable shaft, a lever for rocking said shaft, operating connections between said shaft and the circuit breaker, a key-controlled lock, and means controlled by said lock to lock said shaft, said lock being so located relatively to the lever on said shaft that when its key is inserted, a portion of said key will be disposed in the path of said lever and prevent a complete operative throw of said lever and shaft, the means to lock the shaft being intermediate the shaft and the lock and in angular relation to the shaft.

40 4. In automobile lock means, the combination with means to render a part of an automobile mechanism inoperative, of a manually operable shaft, connections between said shaft and said means, a notched disk carried by said shaft, a plunger to engage the notch of said disk and lock said shaft, a lock, and means operable by the lock to retract said plunger.

45 5. In automobile lock means, the combination with means to render a part of an automobile mechanism inoperative, of a manually operable shaft, connections between said shaft and said means, a notched disk carried by said shaft, a plunger to engage in the notch of said disk and lock said shaft, a lock, means operable by the lock to retract said plunger, means to temporarily lock said plunger in retracted position, and means for operating the temporary locking means to release said plunger.

50 6. In automobile lock means, the combination with means to render a part of an automobile mechanism inoperative, of a manually operable shaft, connections between said shaft and said means, a notched disk carried by said shaft, a plunger to engage in the notch of said disk and lock said shaft, a lock, means operable by the lock to retract said plunger, means to temporarily lock said plunger in retracted position, and means carried by said shaft for operating the temporary locking means.

55 7. In automobile lock means, the combination with means to render a part of an automobile mechanism inoperative, of a manually operable shaft, connections between said shaft and said means, a notched disk carried by said shaft, a plunger to engage in the notch of said disk and lock said shaft, a lock, means operable by the lock to retract said plunger, means to temporarily lock said plunger in retracted position, means carried by said shaft for operating the temporary locking means, said disk also having a V-shaped notch to receive the plunger to hold said disk and shaft against accidental turning.

60 8. In automobile lock means, the combination with a circuit breaker including a movable member, of a manually operable shaft, a disk carried by said shaft and provided with a notch having a beveled wall, a plunger carried by the movable member of said circuit breaker and adapted to enter said notch to permit the circuit breaker to open, and locking means for said shaft.

65 9. In automobile lock means, the combination with a circuit breaker including a movable member, of a manually operable shaft, a disk carried by said shaft and provided with a notch having a beveled wall, a plunger carried by the movable member of said circuit breaker and adapted to enter said notch to permit the circuit breaker to open, locking means for said shaft, and a lock to control said locking means.

70 10. In automobile lock means, the combination with a locking member to lock the clutch control means, of a slide bracket, means connecting said slide bracket and said locking member, a manually operable shaft, locking means for said shaft, a lock to oper-

ate said locking means, and means operatively connecting said shaft with said slide bracket.

11. In automobile lock means, the combination with a locking member to lock the clutch control means, of a slide bracket, means connecting said slide bracket and locking member, a manually operable shaft, locking means for said shaft, a lock

to operate said locking means, a roll-back 10 having pin-and-slot connection with said slide bracket, and a universal coupling between said roll-back and said manually operable shaft.

In testimony whereof, I have signed this 15 specification.

JOSEPH S. LACH.
